PUMP CONSTRUCTION

Howard E. Rose, Peninsula, Ohio, assignor to
Alco Valve Company, University City, Mo., a
corporation of Missouri

Application February 26, 1944, Serial No. 523,982

10 Claims. (Cl. 103—46)

1
The present invention relates to a pump construction, and more particularly to a pump construction for wells in which no moving part is required to be extended from the surface to the bottom of the well. A column of liquid being pumped is employed as the force transmitting means for operating a pumping unit at the bottom of the well.

An object of the invention is to provide a pump of the foregoing type in which alternating high and low pressures in the column of oil being pumped effect actuation of the pumping unit. A particular object of the invention is to provide a pumping unit having a movable piston and a valve mechanism responsive to the high pressure to effect displacement of the pump in a working direction, and operable upon low pressure to release the pumping member.

In the drawing:

Fig. 1 is a vertical sectional view of the pump unit;

Fig. 2 is a horizontal section on the line 2—2 of Fig. 1; and

Fig. 3 is an enlarged section on the line 3—3 of Fig. 2.

The unit will be described in connection with pumping oil, although, as is evident, it may be used in many other connections.

A well liner is shown at 10, it receiving a pump string 11, toward the bottom of which is disposed a pumping unit 12. The pumping unit 12 is located within the supply of oil to be pumped to the surface, and is maintained in this position by a pipe 13 leading to the surface.

The pumping unit 12, usually cylindrical, has a lower flange 14 that seals off the oil supply S in the well from the string above the flange. The member 12 has an inner cylinder 16 that receives a plunger 17 adapted to be reciprocated therein and to extend downwardly through the flange and the bottom of the member 12 into the oil supply. The plunger 17 has a passage 18 extending therethrough with a check valve 19 at the top thereof. The check valve 19 permits flow of oil upwardly through the passage 18, but prevents down flow thereof.

The operation of the plunger and the discharge of oil is controlled through a valve mechanism having a slide valve member 22. The slide valve member reciprocates in a cylindrical passage 23, having an enlargement 24 at the bottom thereof, containing a spring 25 that normally urges the valve member 22 upwardly with a predetermined force.

2

The valve member 22 is cut away to provide a valving space 26.

Referring to Fig. 1, it will be seen that an operating port 27 connects the interior of the pipe 13 with the upper end surface of the valve 22. (This port is suggested in Fig. 3 by dot and dash lines.) Thus, force exerted by pressure within the pipe 13 acts to displace the valve 22 downwardly against the spring 25. The enlargement 24 is ported at 29 (Fig. 3) into the string to permit escape of oil that may leak into the space 24, and which would otherwise obstruct movement of the valve (note that no provision is made to relieve this oil on the down stroke of the valve).

The interior of the pipe 13 is also connected (Fig. 1) by a port 30 that leads to the cylinder 23 below the space 26 on the valve when the valve is in its upper position. (This port is suggested by dot and dash lines in Fig. 3.) The space 26 is in communication with the port 31 when the valve is either up or down. The port 31 leads to the bottom of the cylinder 16 beneath the piston-like head on the plunger 17.

25 A port 33 (Fig. 3) leads from the valve cylinder 23 into the top of the cylinder 16 when the valve 22 is up. A connecting port 34, controlled by a check valve 35, also leads from the top of the cylinder 16 into the string.

Operation

The string 11 is capped in conventional manner and connected with a pipe leading to storage, or other suitable place of disposition of the oil to be pumped. The pipe 13 is connected to a source of intermittent fluid pressure, preferably in the manner shown in applicant's co-pending application, Serial No. 524,196, filed February 28, 1944, for Deep well pumper. The pressure supplied in the pipe 13 attains a high value, sufficient to produce a force to lift the plunger 17 against the head of oil in the string, as will be shown. When it is relieved to low pressure, the force produced is less than the downward force acting upon the plunger.

40 When the applied pressure is low, the spring 25 maintains the valve 22 in its upper position. This spring is of such strength as to overcome force produced by the head of oil in the pipe 13 at the low pressure.

45 Upon the application of high pressure within the pipe 13, the high pressure liquid flows through the port 27, and displaces the valve 22 downwardly. When the valve is down, it connects the ports 30 and 31 to introduce the high

pipe pressure into the cylinder 16 beneath the piston of the plunger 17, forcing that plunger upwardly to expel any oil in the upper part of the cylinder 16. Assuming, as will appear, that there was a charge of oil above the plunger 17, such oil will be expelled outwardly past the check valve 35 and through the port 34 into the string, it being prevented from returning downwardly into the well supply S by the flange 14, so that it is caused to add to the oil within the string. It is, of course, prevented from escaping through the passage 18 of the plunger by the check valve 19.

It will be seen that when the plunger is thus moving upwardly to expel oil, the head of oil within the string will be acting upon the top of the plunger. Consequently, the high pressure applied through the pipe 13 must be of sufficient value to produce a force acting upwardly on the plunger 17 to overcome the downwardly acting force produced by the head of oil within the string. In case the oil is being pumped against a greater pressure than head pressure, the high pressure value in the pipe 13 must be sufficiently high to overcome such applied back pressure.

When the pipe pressure is relieved to its lower value, the valve 22 will return to its upper position under the influence of the spring 25. It thereby cuts off the pressure applying port 30 from the port 31 leading beneath the plunger 17 and causes the port 31 to be connected with the port 33, as is shown in Fig. 3, so that the oil contained beneath the plunger 17 may flow out to the space above the same to join with a new charge of oil. The quantity of oil beneath the plunger 17 is much below the volumetric capacity of the cylinder above the plunger, as is obvious.

The plunger 17, being relieved of upper pressure, descends by gravity, and, in so doing, produces a condition of higher pressure within the oil supply than that within the upper part of the cylinder 16. This usually comes about because of the fact that the oil supply between the liner 10 and the string 11 is at a higher level than the top of the cylinder 16. Such oil flows through the passage 18 and past the check valve 19 to fill the upper part of the cylinder. The pumping mechanism is thereupon positioned for a new cycle upon a subsequent application of high pressure in the pipe 13.

It will be seen that this pumping mechanism requires only a single operating connection with the surface, and that there is no moving mechanical part extending from the pumping unit to the surface. Only the oil within the pipe 13 acts as a moving part.

It is further clear that there is only one piston required, as the valve 22 controls the application of fluid pressures to permit descent of the plunger by gravity.

What is claimed is:

1. In a pumping mechanism adapted to be disposed at the supply of liquid to be pumped, and for use with a conduit for receiving the liquid that is pumped and maintaining the same separate from the supply of liquid, a pump housing, an outlet from the housing for communication into the conduit, plunger means in the housing adapted to be operated in one direction to expel liquid received from the supply into said outlet, an inlet leading into said pump housing and adapted to receive fluid under intermittent relatively high and relatively low pressures, valve means in said pump housing, means connecting the valve means with the inlet to receive the

pressures thereof, said valve means being adapted to be operated from a first to a second position when the pressure in said pipe increases from low to high value, and to return to first position 5 when the pressure decreases from high to low value, port means connected when said valve is in second position to admit said fluid at high pressure to operate the piston means in one direction to expel liquid into the outlet, and said valve means in its first position being adapted to exhaust said fluid to permit the piston means to operate in its other direction.

2. In a pumping mechanism adapted to be disposed at the supply of liquid to be pumped, and for use with a conduit for receiving the liquid that is pumped and maintaining the same separate from the supply of liquid, a pump housing, an outlet from the housing for communication into the conduit, plunger means in the housing adapted to be operated in one direction to expel liquid received from the supply into said outlet, an inlet leading into said pump housing and adapted to receive fluid under intermittent relatively high and relatively low pressures, valve means in said pump housing, means connecting the valve means with the inlet to receive the pressures thereof, said valve means being adapted to be operated from a first to a second position when the pressure in said pipe increases from low to high value, and to return to first position when the pressure decreases from high to low value, port means connected when said valve is in second position to admit said fluid at high pressure to operate the piston means in one direction to expel liquid into the outlet, and said valve means in its first position being adapted to exhaust said fluid to permit the piston means to operate in its other direction, said exhaust means including port means through the valve in its first position admitting fluid from the high pressure side of the piston means to the low pressure side thereof.

3. In a pumping mechanism adapted to be disposed at a supply of liquid to be pumped, and for use with a conduit to receive the liquid that is pumped and to separate the same from the supply, a pump housing, an outlet from the housing for communication into the conduit, cylinder and piston means operable in the housing, means to conduct liquid from the supply to the cylinder, a pressure inlet leading into the housing and adapted to receive intermittent high and low fluid pressures, pressure-responsive valve means operable in the housing from a first position in which the pressure inlet is disconnected from the cylinder and piston means, to a second position in which the inlet is connected with the cylinder to introduce high pressure fluid against the piston means to move the same and expel oil from the cylinder to the outlet, check valve means to prevent return flow of liquid through the outlet, and means connecting the pressure-responsive valve means with the inlet to receive high pressure and low pressure fluid therefrom and to be actuated by said pressures.

4. In a pumping mechanism adapted to be disposed at a supply of liquid to be pumped, and for use with a conduit to receive the liquid that is pumped and to separate the same from the supply, a pump housing, an outlet to provide communication from the housing to the conduit, cylinder and piston means operable in the housing, means to conduct liquid from the supply to the cylinder, a pressure inlet leading into the housing and adapted to receive intermittent high and low fluid pressures, pressure-responsive valve

means operable in the housing from a first position in which the pressure inlet is disconnected from the cylinder and piston means, to a second position in which the inlet is connected with the cylinder to introduce high pressure fluid against the piston means to move the same and expel oil from the cylinder to the conduit, check valve means to prevent return flow of liquid through the outlet, means connecting the pressure-responsive valve means to the inlet to receive the intermittent fluid pressures therein, yieldable means acting on the said valve means in opposition to said fluid pressure, said yieldable means having a force greater than the force produced by the low pressure fluid on the said valve means, but less than the force produced by the high pressure fluid thereon.

5. In a pumping mechanism adapted to be disposed at a supply of liquid to be pumped, and for use with a conduit to receive the liquid pumped and to separate the same from the supply, a pump housing having a cylinder therein, a piston containing plunger operable back and forth in the cylinder, said plunger having a portion smaller than the cylinder adapted to project from the housing into the supply, a passage through said smaller portion leading through the plunger, a check valve permitting flow of liquid through the passage from the supply to the cylinder but preventing back flow therethrough, a port leading from the cylinder to the conduit, a second check valve permitting flow through the port from the cylinder but preventing back flow therethrough, an inlet leading into the housing and adapted to receive intermittent high and low liquid pressures, a control valve, said control valve being movable to connect the inlet to the cylinder at the side of the plunger having the projecting portion, to move the plunger to expel liquid from the cylinder through the port, and said control valve being returnable to connect said projecting portion side of the plunger to the opposite side thereof behind the second check valve, and means to operate the control valve.

6. In a pumping mechanism adapted to be disposed at a supply of liquid to be pumped, and for use with a conduit to receive the liquid pumped and to separate the same from the supply, a pump housing having a cylinder therein, a piston containing plunger operable back and forth in the cylinder, said plunger having a portion smaller than the cylinder adapted to project from the housing into the supply, a passage through said smaller portion leading through the plunger, a check valve permitting flow of liquid through the passage from the supply to the cylinder but preventing back flow therethrough, a port leading from the cylinder to the conduit, a second check valve permitting flow through the port from the cylinder but preventing back flow therethrough, a pressure inlet leading into the housing and adapted to receive intermittent high and low liquid pressures, a control valve, said control valve being movable to connect the inlet with the cylinder at the side of the plunger having the projecting portion, to move the plunger to expel liquid from the cylinder through the port, and said control valve being returnable to connect said projecting portion side of the plunger to the opposite side thereof behind the second check valve, and means to operate the control valve, said last-named means comprising connections to admit the inlet pressures to the control valve whereby the same may be displaced when the inlet pressure is high.

7. In a pumping mechanism, a pump housing, adapted for connection with a high pressure fluid line and a fluid receiving line to conduct fluid pumped by the pumping mechanism, a pressure operated pumping means in the housing, said means being adapted to be moved in one direction by application of high pressure fluid thereto and to be moved in the other direction by relief of said pressure in said fluid, valve means interposed between the high pressure fluid line and the pumping means, yieldable means normally urging the valve means into position to close off the high pressure fluid line from the pumping means, and means responsive to predetermined pressure in the high pressure fluid line to open said valve, and thereby effect admission of high pressure to the pumping means.

8. In a pumping mechanism, a pump housing adapted for connection with a high pressure fluid line and a fluid receiving line to conduct fluid pumped by the pumping mechanism, a pressure operated pumping means in the housing adapted to be moved in one direction by application of high pressure fluid thereto and to be moved in the other direction by relief of said high pressure, valve means in the housing, pressure-responsive operating means for moving the valve means to an open position, said pressure-responsive means being subjected to the high pressure fluid to be operated upon existence of high pressure in said line, yieldable means opposing the pressure-responsive means to effect closing of the valve when said pressure is relieved, connections through the valve and housing to admit high pressure fluid to the pumping means when the valve is open, and connections to relieve said high pressure in said fluid when the valve is closed.

9. In a pumping mechanism, a pump housing, a high pressure fluid inlet in the housing for connection with a high pressure fluid line, a fluid receiving outlet adapted for connection with a fluid receiving line leading from the housing to conduct fluid pumped by the pumping mechanism, a pumping means having a pressure receiving side and a fluid receiving side, the latter being connected with the fluid receiving line, valve means interposed between the high pressure inlet and the pressure receiving side of the pumping means, pressure-responsive means connected with the high pressure inlet for moving the valve means from closed to open position upon existence of high pressure in the inlet, means to move the valve means to closed position upon relief of high pressure in the inlet, connections through the valve in open position to conduct high pressure fluid from the inlet to the pressure receiving side of the pumping means, and connections through the valve in closed position to effect equalization of pressures on opposite sides of the pumping means.

10. In a pumping mechanism, a pump housing, a high pressure fluid inlet in the housing for connection with a high pressure fluid line, a fluid receiving outlet adapted for connection with a fluid receiving line leading from the housing to conduct fluid pumped by the pumping mechanism, a pumping means having a pressure receiving side and a fluid receiving side, the latter being connected with the fluid receiving line, valve means interposed between the high pressure inlet and the pressure receiving side of the pumping means, pressure-responsive means connected with the high pressure inlet for moving the valve means from closed to open position upon existence of high pressure in the inlet, means to move the

valve means to closed position upon relief of high pressure in the inlet, connections through the valve in open position to conduct high pressure fluid from the inlet to the pressure receiving side of the pumping means, connections through the valve in closed position to effect equalization of pressures on opposite sides of the pumping means, and check valve means to prevent back flow of fluid into the housing from the fluid receiving outlet.
